UNITED STATES PATENT OFFICE

2,548,045

AMPLITORQUE CONTROLLABLE PITCH PROPELLER

Harry J. Nichols, New York, N. Y.

Application August 20, 1945, Serial No. 611,481

15 Claims. (Cl. 170—160.3)

1

This invention relates to controllable and reversible pitch propellers, and particularly to propellers for marine use and for hydraulic prime movers, and has for one of its principal objects the provision of a propeller of the character described in which the pitch of the blades can be quickly and accurately regulated while the propeller is in rotation under load and in which the blades will be automatically locked against displacement from the pitch to which they have been set during such regulation.

Another object is to provide an exceptionally simple, compact, and powerful variable pitch propeller hub and blade actuating mechanism which is economical to manufacture, easy to install and service, and which will ensure reliable operation for long periods without special attention or maintenance.

A further object is to provide a controllable propeller which may be readily applied to existing propulsive installations with the minimum of modification of existing components and arrangements, thus securing substantial economies in modernizing installations already in service by the application of controllable pitch propellers thereto.

A further object is to provide a strong and rigid pitch varying mechanism which eliminates any possibility of flutter or vibration of the blades in operation due to excessive elasticity or backlash in the pitch varying mechanism.

A further object is to provide a pitch varying system of adequate angular range, including reversing of the blades, which is capable of changing the blade pitch in micrometric increments, yet also is capable of changing the pitch at a rapid rate for maneuvering and meeting emergencies.

A further object is to provide a pitch regulating system whose operating speed is independent of the speed of rotation of the propeller shaft.

A further object is to provide a construction in which the gears of the primary actuating mechanism are relieved of any strain excepting when the pitch is being varied, thereby reducing the wear on the gear teeth and enabling relatively light gearing to be employed.

A further object is to provide blade actuating mechanism operatively mounted in the hub so that the great stresses due to the powerful hydrodynamic twisting torque on the blades under load are confined to the hub and a rigid and strong blade actuating mechanism of minimum size and cost is obtained.

2

With these and other objects in view, as well as other advantages incident to the improved construction, the invention consists in the various parts and combinations thereof set forth and claimed, with the understanding that the several necessary elements constituting the same may be varied in proportions and arrangement without departing from the nature and scope of the invention as defined in the appended claims.

10 To enable others skilled in the art to comprehend the several underlying features of this invention, that they may embody the same by suitable modifications in structure and relation to meet the various practical applications contemplated by the invention, drawings showing a preferred embodiment of the invention form part of this disclosure, and in such drawings like characters of reference denote corresponding parts in the several views in which

15 Fig. 1 is a side elevation in partial axial section of the unitary flange coupling and driving motor forming part of the invention.

Fig. 2 is a transverse sectional view taken substantially on line 2—2 of Fig. 1.

20 Fig. 3 is a side elevation in axial section of the hub of a variable pitch propeller and drive shaft therefor embodying certain features of the invention.

Fig. 4 is a transverse cross section of the propeller of Fig. 3 taken substantially on line 4—4 of Fig. 3.

25 Fig. 5 is a top view of the hub of Fig. 3 shown with the blade and blade mounting dismantled so as to disclose the construction of the slide portion of the cross-head and other details.

Fig. 6 is a transverse cross section of the gear mechanism taken on lines 6—6 of Fig. 3.

Referring now to the drawings and particularly to Figs 1 and 2, a preferred construction 40 of a controllable pitch propeller system embodying the invention is shown as comprising a hollow main shaft 10, as for example the shaft of a prime mover, having a collar or annular flange 11 upset or otherwise provided thereon at one end, and a propeller shaft 30 having mounted thereon a demountable flange 31, the two being connected in driving relation by means of a novel unitary flange coupling 20 in which is housed a pitch changing motor and other mechanism to be described in detail hereinafter.

45 The actuating motor is preferably a polyphase induction motor having a squirrel cage rotor 15 mounted on a shaft 14 journalled in bearings suitably mounted in end shields 16, 17 in concentric relation to the bore of a laminated stator

13 having typical distributed windings 19. The end shields and stator are suitably assembled to tubular shell or frame 21 as shown or in any preferred manner, thereby to provide a complete motor unit.

A hollow cylinder or barrel 22 comprises the main structural component of the special flange coupling. Suitably mounted on barrel 22 but insulated therefrom by an insulating band 23 are two series of slip rings designated by 24 and 25 respectively, and riding thereon are brushes 26 and 27, shown schematically since the construction of slip ring and brush assemblies are well known. Insulated conductors 28 provide a path for current from slip rings 24 to winding 19, while insulated conductors 29 provide electrical connections from slip rings 25 to electrical transmitter 13 mounted on end shield 16 and forming part of an electrical pitch indicator system, but not a part of the present invention.

The details of the electrical pitch indicator system, including electrical transmitter 13, hereof, are shown and described in my copending application, Serial No. 618,643, filed September 26, 1945. For present purposes, it is deemed sufficient to point out that electrical transmitter 13 is mounted inside coupling 20 in operative relation to motor shaft 14, and that the internal mechanism of electrical transmitter 13 is driven by extended shaft 40.

A circular flange plate 34 is suitably secured by screws to barrel 22 and the motor is mounted on plate 34 by screws tapped into end shield 17, or otherwise as desired, thereby providing a unitary assembly for the entire flange coupling, including the motor and electrical transmitter. The flange coupling 20 is assembled to the shaft flanges by cap screws 32 passing through suitable longitudinal holes in flange 31, split shaft-locking ring 33 and flange plate 34, and screwed into threaded holes in barrel 22; while cap screws 12 pass through longitudinal holes in flange 11 and are screwed into threaded holes in barrel 22, whereby when these cap screws are tightened these parts are tightly clamped together in rigid driving relation. Demountable flange 31 is keyed to propeller shaft 30 by multiple keys 38, one key being shown.

Motor shaft 14 is provided at one end with an extended output shaft 40, extending into electrical transmitter 13 for driving same, and at the other end with a second splined output shaft 41. An internally splined sleeve 42 couples output shaft 41 to the splined end 43 of torque shaft 45, the latter being mounted rotatably and concentrically in the bore of tubular propeller shaft 30 by a series of sleeve bearings 44 assembled tightly on torque shaft 45, one of the bearings 44 being shown, while other bearings are mounted at several points along the shaft in well known manner.

Flange plate 34 is provided with a peripheral lip 35 and barrel 22 with a projecting shoulder 36, the space between the lip and the shoulder providing a groove in which is assembled an annular oil sealing ring 50 of special construction to enable lubricating oil to be supplied to the rotating shaft assembly. The lubricating oil is maintained at a certain hydrostatic pressure and fills all the void spaces in the flange coupling, motor, propeller shaft and hub, thus providing continuous oil lubrication to all the working and bearing surfaces.

The oil sealing ring 50 comprises a metallic bellows of thin non-corrodable metal, such as

stainless steel, the lips of which exert a light spring pressure on the adjacent side walls of the groove. This spring pressure is augmented by the oil pressure, which as stated is maintained at a level somewhat greater than the hydrostatic pressure on the propeller hub. It is intended that a slight leakage of oil shall occur at the joint between the bellows lips and the walls of the groove, thereby providing continuous oil lubrication of the sliding metallic surfaces. Two split rings 51, preferably of vulcanized fibre or the like, are assembled in the inner folds of the bellows and are loosely fitted to the shaft, these split rings serving to prevent the lips of the bellows from riding on the bottom of the groove, thus avoiding wear at the edges of the bellows lips. A circular tube 52 is mounted in the middle fold of the bellows as shown, being secured thereto by soldering or otherwise as desired. A series of radial holes 53 extend through the inner walls of the tube 52 and the middle fold of the bellows, to enable oil flowing in tube 52 to enter the sealed space in the bellows, and via radial holes 54 in barrel 22 to reach the interior of the coupling. The bellows and the ends of tube 52 are brazed into a fitting 55 provided with a threaded stem 56 adapted to mate with hollow nut 57 and in combination therewith to provide a tight connection with oil supply tube 58, all in well known manner.

It will be observed that the construction of the novel unitary flange coupling described obviously permits of ready and accurate assembly of the various parts, and of ready disassembly to replace the oil sealing ring 50, should this become necessary, the oil sealing ring being the only part which is normally in rotation relative to the shaft and therefore being most subject to wear.

Referring now to Figs. 3 to 5 inclusive, and particularly to Fig. 3, which show one form of propeller hub construction according to the invention adapted for use with the motor drive of the unitary flange coupling previously described, the propeller hub 60 is fixed tightly to the flange 39 of the tubular propeller shaft 30 by a series of circularly arranged cap screws 61 (one being shown) or otherwise as desired. A hub cap 80 is secured to hub 60 by a plurality of longitudinally disposed cap screws 61, or otherwise as desired. The hub 60 is formed with a plurality of radially extending circular sockets 62, and has longitudinal ribs 63 diametrically crossing thereunder, each rib having formed integral therewith a center pin 64 with its radial axis concentric with the bore of the associated socket. Each socket 62 is step bored to receive a closely fitting bearing ring 65 adapted to be secured therein by multiple cap screws 66 as shown. Blades 70, each having a root portion or boss 71 to which a crank pin ring 72 having an integral crank pin 73 can be attached by multiple cap screws 74, are rotatably mounted in the sockets 62 in the following manner: Each crank pin ring 72 is provided with a concentric bore lined with a bearing 75, rotatably fitted to center pin 64, and with a step shoulder 69. (The cross-head 100 is assumed to be in place as shown in Fig. 3, and the slipper blocks 103 to be in the position shown in Fig. 5.) The crank pin 73 is entered into the bore of the slipper block and ring 72 lowered into socket 62. After the ring 72 is in place, bearing ring 65 is assembled in the socket and cap screws 66 screwed tightly in place. A flat, thin cover ring 67 is placed in the socket to cover the heads of cap screws 66 and a non-ferrous sealing ring 68, having an arched section

to provide a limited amount of resiliency when subjected to pressure, is placed in the socket over the cover ring. The blade root 71 is then centered on the center pin 64 and cap screws 74 inserted in the threaded holes in the crank pin ring 72 and screwed up tight, thereby placing the sealing ring 68 under a predetermined pressure insufficient to squeeze out the oil film between the sealing ring and the blade root, but sufficient to prevent any material leakage of oil.

The construction described enables the blade to be rotated readily and accurately while providing adequate bearing area to accommodate the powerful forces on the blade while in rotation under load, and also provides a durable seal to prevent excessive leakage of lubricating oil at the blade sealing joint, yet permits a slow seepage of oil outwardly to prevent the entrance of water into the hub. The blade mounting and sealing arrangement described is known to give reliable operation during years of operation.

Referring again to Figs. 3 to 6 inclusive, one form of novel blade actuating mechanism according to the invention comprises generally a power screw jack mounted axially in the hub 60 and operatively connected to turn the blades, and differential gearing mounted at the end of the hub opposite to the propeller shaft, which gearing receives torque from torque shaft 45 and supplies greatly amplified torque to the screw member 90 of the power screw jack.

Torque rod 45 extends coaxially through hollow power screw 90 and is mounted rotatably in bearing 82 carried by an integral strut 83 of hub cap 80 and in bearing 84 carried in the bore of power screw 90.

Mounted tight on rod 45, preferably by a tight splined connection as shown, is a planetary carrier assembly comprising two discs 85, 86 assembled together by cap screws 87 and stud sleeves 88. (See Fig. 6.) These discs carry two tight short axles 89, on which are rotatably mounted two planetary pinions P1 and P2, which pinions have the same number of teeth, but the teeth on the two halves of pinion P2 are staggered in order to mesh properly with the two internal gears G1 and G2 of the differential gear train. Internal gear G1 is rigidly fixed to hub 60 by a plurality of cap screws 91 as shown or as may be desired.

Internal gear G2, which is the driven gear in the gear train, is a component part of the power screw, and may have internal teeth cut on the inner periphery of flange 92 as shown or may be an assembled component. To provide differential action, gears G1 and G2 vary by one tooth; for example G1 may have 55 teeth, while G2 may have 56 teeth. As is well understood in the gear cutting art, the pitch circles to which the gear teeth are cut are suitably adjusted to provide smooth meshing of the pinions with the gears, even though the gears have a different number of teeth.

Power screw 99 is journaled in a bearing 93 in the shaft end of the hub and in a cylindrical bore 94 at the opposite end of the hub. A thrust plate 95 is set in the bore 94 of the hub to provide one thrust bearing surface for flange 92, and a bearing ring 96 is assembled between flange 92 and the rim of G1 to provide a second thrust bearing surface. In this manner, the thrust on power screw 99 due to the blade reaction is taken up in structural parts within the hub by adequate thrust bearing surfaces.

A triangular cross-head 100 is mounted as a nut on power screw 90 in such manner that the

rotation of the power screw will translate the cross-head axially in the hub. In order to permit of assembly to the cross-head in the one piece hub (which is the generally preferred and simplest construction), the slide portions 101 of the arms of the cross-head are made separate; being assembled after the cross-head is in place by cap screws 77, access for that purpose being obtained through the blade sockets before the blades are assembled as shown in Fig. 5. Slipper blocks 103, each having a bore to receive one of the crank pins 73 of crank pin rings 72, are closely fit in the transverse slide portions of the cross-head. Further, the cross-head is provided with a longitudinal key 78 which slides in a key way in one of the ribs 63 to resist the tendency of the cross-head to rotate when the power screw is rotated under load. The cross-head is also preferably formed with central bosses which serve as stops against the hub 60 or plate 95 at the end of the stroke of the cross-head in event the normal working stroke is exceeded and thus function as pitch limit stops without damage to the operating mechanism.

The operation of the construction described is as follows: When the pitch is to be varied, the actuating motor is electrically energized to produce rotation of rotor 15 in one rotary direction or the other, thereby rotating torque shaft 45 in the same direction. Planetary carrier 85 is rotated accordingly and pinions P1 and P2 revolve in planetary motion in mesh with stationary gear G1 and driven gear G2. At the end of one revolution of the planetary carrier these pinions by planetary action have meshed with all the teeth of gear G1 (assumed to have 55 teeth) and with an equal number of teeth of gear G2 (assumed to have 56 teeth). Thus gear G2 is caused to advance (or lag) gear G1 by one tooth pitch, producing a corresponding differential rotation of the two gears. Since internal gears of the type described are known to be highly efficient, the torque amplification factor in the gear stage described is substantially equal to the speed reduction ratio. In the example chosen, since the speed reduction ratio is 56 to 1, the torque amplification factor would be approximately 55X.

Since gear G1 is fixed to the hub, rotation of gear G2 relative to gear G1 produces rotation of power screw 90 in the threaded bore of cross-head 100 thereby causing axial translation of the cross-head in the hub and consequent rotation of the blades in their sockets.

Referring now to Figs. 3 to 5, it will be noted that the arms 101 of cross-head 100 are fitted with transverse slide channels 102 adapted to receive slipper blocks 103 each having a bore 104 fitting a crank pin 73 of one of the crank pin rings 65, each of which is attached to the root portion of one of the blades 70. As may be best seen in the upper part of Fig. 5, when cross-head 100 moves in an axial direction, each of the crank pins 73 will be forced to rotate in unison, the slipper blocks 103 sliding in the slide channels 102 as indicated to accommodate the transverse component of the crank pin motion. It is to be noted that the construction described enables a rigid and closely fitted operative connection to be employed between the power screw and the blades, thereby avoiding any degree of back-lash or elasticity likely to permit of vibration of the blades when under load. It is also to be noted that the power screw-jack can readily be made self-locking; i. e. the blade reaction

rendered incapable of causing rotation of the power screw, and this is the preferred construction. Furthermore, the differential gearing described is inherently self-locking, since gears G1 and G2 are positively locked against relative rotation by pinions P1 and P2, except when these pinions are driven in planetary revolution. The blade actuating system described is therefore inherently self-locking in any position to which it is set; that is, the system cannot be 10 actuated in reverse by the reaction of the blades.

The operation of the entire blade actuating system of the invention is as follows: Normally, when the propeller shaft is in rotation, all the parts rotate bodily with the shaft and are at rest relative to each other, except that the brushes 26 and 27 are stationary and ride on the rotating slip rings 24 and 25. To vary the pitch, the motor is supplied with current from a reversing controller, not shown, via brushes 26, slip rings 24 and the internal conductors 28 to energize windings 19 and thereby produce rotation of the rotor 15 in one direction or the other. Torque shaft 45 is driven by rotor 15 through coupling sleeve 42 to rotate planetary carrier 85, thereby causing planetary revolutions of the pinions P1 and P2 in internal gears G1 and G2.

The differential gear action previously described causes gear G2 to progress at reduced speed and amplified torque relative to gear G1, thereby forcing rotation of power screw 99 in the threads of cross-head 100 and axial translation of the cross-head. The motion of the cross-head is transmitted by slipper blocks 103 to the crank pins 13, forcing rotation of the blades. When rotation of the blade ceases, the blades remain set at that pitch until subsequent variation of the pitch by actuating operation as described. It is of course obvious that the rate of pitch adjustment is entirely independent of the shaft speed, and therefore can be accomplished with equal facility with the propeller shaft at rest or in rotation at any speed. This is an important feature in providing reliable and rapid pitch regulation under all operating conditions.

It is further to be noted that because of the two-stage speed reduction and torque amplification provided, the speed reduction ratio may readily be as much as 3000:1 or even greater, and the torque amplification factor 2000 or more times the motor torque. Hence a small, high speed actuating motor can be employed to advantage, and the pitch of the blade can be varied slowly in micrometric increments or rapidly over the range from full forward to full reverse by control of the motor speed. Since the art of controlling the speed of motors is highly developed, it follows that the pitch varying system described combines great flexibility and ease of control combined with efficient use of the actuating power.

It is thus apparent that by greatly reducing the factor of gear wear, by providing a minimum of gearing of highly efficient type, by relieving the gears from load except while the pitch is varied, by confining the major operating forces to the hub structure, by providing a double lock of the blade setting, by eliminating external mechanical drive, and by inherent simplicity, economy, reliability and other features, the controllable pitch propeller system of the invention overcomes the disadvantages which have limited the application of mechanical variable pitch propellers of the prior art.

I claim:

1. In combination with a variable pitch propeller having a hollow propeller shaft, a hollow hub fixed thereon, and a plurality of axially rotatable blades mounted on said hub, of mechanism operatively mounted substantially within said hub for rotating said blades axially in unison to vary their pitch comprising, a power screw-jack including a hollow rotary driving screw and a translatory non-rotatable driven nut-member mounted coaxially with respect to each other and said hub, means adapted to convert translatory motion of said driven member to axial rotary motion of said blades for operatively connecting said nut-member to rotate said blades axially in unison, torque amplifying differential gearing mounted coaxially in said hub and operatively connected to rotate the driving screw of said power jack, and means including a torque shaft passing coaxially through said driving screw for applying driving torque to said differential gearing.

2. A variable pitch marine propeller having, in combination, a hollow hub, a plurality of axially rotatable blades mounted on said hub, and mechanism operatively mounted within said hub for rotating said blades axially in unison under load comprising, a screw-jack including a hollow rotary driving screw and a translatory driven nut mounted coaxially in said hub, means adapted to convert translatory motion of said nut to axial rotary motion of said blades for operatively connecting said driven nut to said blades in common, differential gear means adapted to increase greatly the driving torque operatively connected to said driving screw, and power means including a torque transmission shaft passing coaxially through said driving screw for applying reversible driving torque to said gear means.

3. In a variable pitch marine propeller, in combination, a hollow hub, a plurality of blades mounted for axial rotation on said hub to vary their pitch, and mechanism mounted within said hub for applying greatly amplified driving torque to rotate said blades axially in unison while under load comprising, a screw-jack including a hollow rotary jack-screw mounted coaxially with respect to said hub and a translatory driven nut-member mounted non-rotatably on said jack-screw, means for converting translatory motion of said nut-member to axial rotary motion of said blades operatively connecting said nut-member to said blades, differential gear means characterized by a large torque gain ratio operatively connected to rotate said jack-screw; and power means including a torque shaft passing coaxially through said jack-screw for applying reversible driving torque to said differential gear means.

4. In a reversible variable pitch marine propeller, in combination with a hollow main hub structure having a plurality of blades mounted for axial rotation thereon to vary their pitch, of mechanism operatively mounted substantially within said hub structure for rotating said blades axially in unison while under load comprising, a screw-jack having a rotary driving screw and a translatory driven nut member mounted centrally with respect to said hub, a mechanical movement operatively connecting said member to said blades so as to rotate them axially by a translatory movement of said member, and power means including a torque transmission shaft passing coaxially through said screw-jack mechanism and differential gearing characterized by a large torque multiplying ratio operatively con-

nected to be driven by said shaft for applying greatly amplified driving torque to said rotary driving screw.

5. A controllable and reversible pitch propeller system including a tubular propeller shaft and having, in combination, a liquid-tight hollow hub structure fixed coaxially on said shaft comprising a one-piece hub having radial sockets fixed tightly to said shaft and a liquid-tight cap secured tightly thereto, a plurality of axially rotatable blades having journals secured rotatably but tightly in the sockets of said hub; and mechanism operatively mounted within said hub for applying greatly amplified torque so as to rotate said blades axially in unison for the purpose of varying and reversing the pitch of said blades while under load comprising, a power screw-jack mounted coaxially in said hub between said journals, means for converting translatory motion to rotary motion operatively connecting said screw-jack to said blades, differential gearing mounted coaxially in said hub in driving relation to said screw-jack, and power transmission means including a coaxial torque shaft extending through said propeller shaft and said screw-jack for applying reversible driving torque to said differential gearing.

6. In combination with a variable pitch marine propeller having a hollow hub and a plurality of blades mounted axially rotatably thereon to vary their pitch, of mechanism operatively mounted within said hub for varying the blade pitch in unison comprising, a power screw-jack having a rotary driving screw extending rotatably within and coaxially of said hub mounted in bearings so as to be held against axial movement, and a translatable nut in the form of a cross-head mounted coaxially on said screw so as to be translated thereby and guided by said hub to slide axially without rotation, a sliding block linkage comprising a pin, a slot and a sliding block interposed therebetween operatively connecting said cross-head to said blades so as to turn said blades about their axes, and power means including differential gearing for applying reversible driving torque to said rotary screw.

7. In combination with a variable pitch propeller including a hollow hub, of a plurality of blades mounted in said hub for axial rotation each about its longitudinal axis to vary their pitch, and of mechanism operatively mounted within said hub for rotating said blades axially in unison comprising, a power screw-jack mounted coaxially in said hub between said blades including a rotary jack-screw rotatably mounted in bearings in coaxial relation to said hub and a translatable combined nut-and-cross head mounted on said screw and guided by said hub for coaxial movement only, a mechanical movement for converting translatory motion of said nut into rotary motion of said blades about their axes comprising a slot, a pin, and a sliding block working between them, power means including differential gearing for rotating said screw, and thrust bearing means for supporting said screw against axial displacement.

8. A variable pitch marine propeller having, in combination, a hollow propeller shaft and a hollow hub mounted coaxially on one end thereof, and a plurality of blades mounted in radial sockets of said hub for rotation each about its own longitudinal axis; torque multiplying mechanism operatively mounted within said hub comprising a power screw-jack, including a hollow

rotary jack-screw extending rotatably within and co-axially of said hub, and differential gearing having a large torque gain ratio connected to drive said jack-screw; power means for applying torque to said differential gearing including a torque shaft passing coaxially through said propeller shaft and said jack-screw, and means operatively connecting said power jack to said blades for rotating said blades axially in unison.

10. In combination with a reversible pitch marine propeller including a tubular propeller shaft having a hollow hub mounted coaxially on one end thereof and a plurality of blades mounted for axial rotation in said hub; of torque amplifying mechanism operatively mounted within said hub comprising planetary differential gearing coaxially disposed within said hub, a power screw-jack including a hollow rotary jack-screw mounted coaxially within said hub so as to be driven by said gearing, a mechanical movement mounted within said hub for connecting said power screw-jack to said blades to rotate them axially in unison; a torque shaft extending rotatably and coaxially through said jack-screw and operatively connected to drive said planetary differential gearing; and power means carried by said propeller shaft at the end opposite to the hub for applying reversible torque to said torque shaft.

30. 10. In a controllable and reversible pitch marine propeller system including a tubular propeller shaft, a hollow hub, and axially rotatable blades carried by said hub, in combination, torque multiplying mechanism operatively mounted within said hub for rotating said blades axially in unison comprising planetary differential gearing mounted coaxially in said hub, and means including a screw-jack mounted between the inner ends of said blades operatively connecting said gearing to said blades so as to rotate the latter axially; a torque shaft extending rotatably in and coaxially through said propeller shaft and into said hub and operatively connected to drive said planetary gearing; and an electrically energized power unit, including a reversible electric motor, carried by said propeller shaft at the end remote from said hub and operatively connected to drive said torque shaft.

11. A controllable and reversible pitch propeller system having, in combination, a drive shaft, a liquid-tight tubular propeller shaft, a liquid-tight hollow hub having radial sockets fixed tightly on one end of said propeller shaft, and blades having journals rotatably but tightly secured in said sockets; mechanism within said hub for rotating said blades in unison including a power screw-jack mounted between said journals, and torque multiplying planetary differential gearing mounted operatively within and coaxially of, said hub; a torque shaft extending coaxially through said propeller shaft and into said hub and operatively connected to drive said gearing, and a liquid-tight combination power unit and coupling drivingly connecting said drive shaft to said propeller shaft.

12. In a variable-pitch propeller system, the combination of a hollow hub, a plurality of blades carried thereby and so mounted as to be capable of angular adjustment each about its own longitudinal axis for varying the effective pitch of the propeller, and mechanism operatively mounted substantially within said hub for turning said blades axially in unison while operating under load comprising, planetary differential gearing mounted coaxially in the outer end of

said hub, a power screw-jack operatively mounted centrally in said hub between the inner ends of said blades and including a rotary jack screw operatively connected to said gearing so as to be driven thereby, a sliding block linkage connecting said screw-jack to turn said blades each about its own axis, and power transmission means operatively connected for driving said gearing.

13. In a controllable and reversible pitch marine propeller including a tubular propeller shaft and a hollow hub having blades rotatably mounted therein, in combination, torque amplifying mechanism within said hub for rotating said blades in unison including a power hollow screw-jack including a jack-screw mounted rotatably and coaxially in said hub, speed-reducer differential gearing mounted in said hub in the end opposite said propeller shaft and operatively connected to drive said jack screw, and a torque transmission shaft passing coaxially through said jack-screw operatively connected for applying driving torque to said speed reducer differential gearing.

14. In a controllable and reversible pitch liquid propeller, the combination of a hollow hub, blades carried thereby and so mounted as to be capable of angular adjustment each about its own longitudinal axis, torque amplifying mechanism mounted operatively in said hub for angularly adjusting said blades, said mechanism including a power jack having a hollow rotary jack-screw mounted centrally within, and coaxially of, said hub and differential gearing mounted coaxially in said hub for driving said jack-screw, and power means including a torque transmission shaft passing coaxially through said jack-screw operatively connected for driving said differential gearing.

15. In a variable pitch marine propeller, the combination of a tubular propeller shaft, a liquid-tight hub fixed tightly to the out-board end thereof, a plurality of blades carried by said hub and so mounted as to be capable of angular adjustment each about its own longitudinal axis, a hollow rotary power screw rotatably held centrally and coaxially within said hub, a combined nut-and-crosshead member mounted coaxially

on said screw, guide means inside said hub holding said member against rotation with said screw but permitting axial movement thereon, means operatively connecting said member to said blades to turn each about its own axis by axial movement of said member on said screw; and means for rotating said power screw including differential gearing operatively mounted coaxially in said hub, and a torque transmission shaft extending co-axially though said power screw operatively connected to drive said differential gearing.
